UNITED STATES PATENT OFFICE.

GEORGE HAZZARD BLAKER AND JOHN HENRY TOWERS, OF MAUMEE, OHIO.

PROTECTIVE VEST.

No. 921,352.

Specification of Letters Patent. Patented May 11, 1909.

Application filed January 9, 1908. Serial No. 471,421.

To all whom it may concern:

Be it known that we, GEORGE H. BLAKER and JOHN H. TOWERS, citizens of the United States, residing at Maumee, county of Lucas, and State of Ohio, have invented certain new and useful Improvements in Protective Vests, of which the following is a specification.

Our invention relates to vests and particularly to protective vests to be worn by 10 policemen, and the object of our invention is to provide a protective vest which shall cover the vital parts of the body and protect the same from bullet or knife wounds.

15 A further object of our invention is to provide a vest as mentioned which shall be flexible and of light weight to the end that the same may be worn without discomfort. Other objects will appear hereinafter.

20 Our invention consists generally in a vest formed of tough fabric such as canvas and shaped to fit snugly the body of the wearer. This is covered by a plurality of separate plates formed of thin steel. The plates are 25 secured to strips of tough flexible material as by riveting, the edges of the plates overlapping each other and the strips to which the plates are secured, are secured, preferably by stitching, to the vest.

30 Our invention further consists in various details of construction and arrangements of parts all as will be fully described herein-after and particularly pointed out in the claims.

35 Our invention will be more readily understood by reference to the accompanying drawings forming a part of this specification and in which,

Figure 1, is a front view of a protective 40 vest embodying our invention in its preferred form, Fig. 2, is a detail view illustrating the manner of attaching the plates, Fig. 3, is a similar view illustrating a slightly modified form of plate, Fig. 4, is a similar 45 view illustrating a modification of the manner of attaching the plates and Fig. 5, is a section on the line x—x of Fig. 4.

Referring now to the drawings 1 indicates 50 a vest formed of fabric such as canvas, open at the front as at 2. The vest is shaped as at 3 to conform to the neck of the wearer and is provided with the usual arm holes 4. The lower edge of the vest is extended as at 5 to cover all of the vital parts of the body.

55 6 indicates small metal plates which are

preferably formed of thin steel and which cover the entire vest portion 1. The plates 6 are first secured to flexible strips 7 as by rivets 8 and are fixed to the strips 7 so that their adjacent edges overlap as shown clearly 60 in Figs. 2 to 5 inclusive. The strips 7 are then successively stitched to the fabric 1 so that the plates 6 attached to each strip will overlap those on the strip beneath. It should be noted that by this construction the 65 plates are not secured to each other hence the vest is substantially as flexible as an ordinary vest and may be worn with comfort.

In Fig. 3 we have illustrated a slight modification in the plates. In this form the upper overlapping corner of each plate is cut away as at 9 so that the plates in the row do not overlap at the point where they are secured to the strips 7, that is at their upper edges. This increases the flexibility of the 75 device. Each plate is preferably substantially rectangular except that its lower end is rounded, and are preferably of greater length than width, although we do not limit our invention to this particular shape. 80

In Figs. 2 and 3, we have illustrated the plates in each row lapped in the same direction, but if desired the plates in each alternate row may be lapped in the opposite directions as illustrated in Figs. 4 and 5. This 85 latter construction affords greater protection, particularly from knife wounds as it is obvious that if a knife should penetrate between the plates of one row it will glide harmlessly along the plates of the row beneath. 90 To fasten the vest one edge of the front is provided with a plurality of tabs 10 having button holes 11 and the opposite edge is provided with buttons 12 preferably riveted to the plates 6 and at sufficient distance from 95 the edge to maintain the edges in overlapped position.

Having described our invention what we claim as new and desire to secure by Letters Patent is:

1. A protective vest comprising a garment formed of flexible material, strips of flexible material secured to said garment, a plurality of metal plates secured at their upper edges to each of said strips, the edges of said 105 plates overlapping and the upper corners of the overlapping edges being cut away, substantially as described.

2. A protective vest comprising a garment formed of flexible material in combination 110

with a plurality of metal plates secured to said garment in rows, the edges of the plates in each row overlapping and each row of plates overlapping the adjacent rows, and the plates in the successive rows lapping in opposite directions, substantially as described.

In testimony whereof we have signed our

names to this specification in the presence of two subscribing witnesses.

GEORGE HAZZARD BLAKER.
JOHN HENRY TOWERS.
